TRAFFIC ACTUATED SIGNALING APPARATUS

Harry A. Wilcox, Norwalk, Conn., assignor to
 Automatic Signal Corporation, East Norwalk,
 Conn., a corporation of Delaware

Application December 15, 1939, Serial No. 309,314

12 Claims. (Cl. 177—337)

The present invention relates generally to traffic control apparatus of the traffic actuated type employed for the control of right of way of traffic on streets, highways and roads. This invention relates more particularly to improved traffic signal control apparatus of this type primarily for use at each of a plurality of intersections of cross roads along a main road to provide coordinated signaling at the several intersections in predetermined time relation.

Systems have been known for some time in the prior art in which the signal controllers at a series of intersections along a main road are arranged to accord right of way to the main and cross roads alternately at periodic intervals at each intersection in accordance with a prearranged "progressive" or "synchronized" pattern for the entire series of intersections, so that groups or platoons of traffic moving on the main road at the predetermined speed for which the system is designed will in the case of a progressive system pass through all the intersections without stopping, and will in the case of the synchronized system move for long distances along the main road before right of way is interrupted, with such interruption of right of way being made at all intersections simultaneously.

It has also been known in the prior art that the controllers at such intersections may be of the traffic actuated type in which traffic detectors are placed for actuation by cross road traffic approaching the intersection and right of way is not transferred from the main road to the cross road at an intersection except in response to actuation of the traffic detector. In this type of system in order to maintain assured main road right of way periods at the several intersections in the desired time relation for movement of main road traffic the transfer of right of way from the main road to the cross road in response to cross road traffic actuation is permitted to occur only at the end of what would be the main road right of way period at each intersection were the controller there to be of the periodic, non-traffic-actuated type.

The coordinated traffic actuated system can be visualized as having a continuously operating background cycle for all signal controllers at all intersections in the system in predetermined time relation, and the signal controller at any one intersection is connected to be operated through a local signal cycle in accord with the background cycle in response to traffic actuation at that intersection.

One type of periodic traffic signal controller 55

in the prior art employs a signal switching cam-shaft of the step-by-step type and a solenoid operated ratcheting device for stepping the cam-shaft through its signal cycle, the solenoid being operated momentarily from time to time over an operating circuit including contacts operated by pins in a continuously rotating dial. In such type of controller one revolution of the dial determines the total time length of the signal cycle and the pins are placed in desired positions in the rotating dial so as to divide the total cycle for the several steps of the camshaft.

In accordance with one form of the present invention a traffic actuated switch is interposed 15 in the operating circuit for the solenoid in a controller of this type, between the solenoid and the contacts operated only by a particular pin for operating the camshaft at a particular point in its cycle; which point is preferably chosen as the 20 end or near the end of the main road right of way period where the traffic actuated switch is actuated by traffic in the cross road for example, so that the camshaft cycle can be initiated from its main road right of way rest position only at 25 the predetermined point at which the particular pin is located in the cycle of the continuously rotating dial; and thus an improved traffic actuated signaling apparatus is provided which is 30 adapted to form a unit in a coordinated system having a fixed total cycle, and which apparatus provides for safe and ready flexibility of adjustment of the several signal periods of the cycle without the possibility of exceeding the total cycle by such adjustment so as to interfere with co- 35 ordination with other units.

It is a general object of the invention to provide an improved traffic signaling apparatus in which a step-by-step cyclic signal controller is initiated to provide a signal cycle under control 40 of and at a predetermined point in the cycle of a cyclic stepping device in response to traffic actuation.

It is also an object of the invention to provide 45 an improved traffic actuated signaling apparatus of a type in which the total length and subdivision of the signal cycle into predetermined parts is fixed by one rotary member and the combinations of signals to be displayed in the several 50 different parts of the cycle is determined by a second rotary member controlled by the first member responsive to traffic actuation.

Other objects will appear from the disclosure and claims below.

Apparatus embodying the invention will now

be described and its operation explained in connection with the accompanying drawing.

On the left side of the drawing is represented the intersection of a main road A and a cross road B together with the usual red, green and yellow colored signal lights AR, AG, and AY for the main road and BR, BG, and BY for the cross road respectively for indicating to traffic when to stop and go and when the signal is about to change, and the control apparatus I for the signals.

Traffic detectors D1 and D2 are located in the cross road B to be actuated by traffic therein.

At the right side of the drawing is shown another intersection along the main road A, the one shown being at a cross road C and provided with signals, detectors and controllers II which is similar in construction to controller I. Both controllers together with all others which may comprise the system are connected to a common AC power source.

Considering controller I at the intersection of A and B roads briefly, the controller or timer is of the rotating dial type, the rotating dial or disc being driven at constant speed by a synchronous type motor M having the same cycle time as the other controller motors and keeping closely in step with such other motors as for example with motor M' shown, as both are furnished with power from a common AC power supply to all the motors.

By means of pins or studs in the rotating disc and a linking arrangement shown herein to be comprised of contacts adapted to be actuated by the pins to energize the solenoid S of a solenoid-operated ratcheting mechanism, a camshaft CS is operated step-by-step through a cycle of operation. Contacts operated by cams on the shaft control the display of signal indications. Although the disc rotates continuously the aforementioned stepping of the camshaft through a cycle of signal indications is not initiated until a unit of traffic on the cross road approaches the intersection to actuate a detector located in or near the cross road approach and affects the controller to prepare a circuit for stepping the camshaft from the resting position at the first subsequent moving of the disc through a predetermined point in the cycle of the latter. The camshaft thereafter is notched through one cycle and back to a resting position by action of the pins mentioned, and in its cycle of operation the camshaft causes the transfer of right of way, with the usual yellow clearance or change periods intervening, from the main road to the cross road and back to the main road where the right of way remains until another cross road detector actuation has prepared the circuit for again stepping the camshaft from its resting position and the rotating disc has again reached the predetermined or synchronizing point in its cycle.

Provision is made to lock-in or "remember" actuations of the cross road detectors by vehicles which actuate the detector so late in the cross road right of way display period that they have insufficient time to cross the intersection or which actuate the detector during the main road right of way period, thus preparing the way for another cycle of camshaft operation in which right way is again transferred to the cross-road.

The details of construction and operation of an embodiment of the controller will be more

readily comprehended from the following more detailed description.

Considering for example the intersection of roads A and B shown at the left side of the figure of drawing, vehicle actuated detectors D1, D2 are located in the cross road approaches to the intersection. These may be of the pressure operated pavement type which operate during the passage of a vehicle across them to close an electric circuit. Suitable photo-electric and electro-magnetic detecting devices and other means of detection are well known in the art and any of these may be utilized instead of the pressure type.

15 The controller I is of the rotating disc type and includes a self-starting synchronous type motor M, which may be of the general type well known for synchronous electric clocks, for example. The motor M is connected to leads from 20 an AC power source, which is common to all the controllers forming part of the system, for driving continuously a disc 10 either directly or by a system of gearing. A plurality of pins or studs 11 are removably mounted in the face of disc 10 and cooperate with a pair of contacts 13 to close a circuit through the contacts and another pin 12 also removably mounted in the face of the disc independent of pins 11 cooperates in similar fashion with the contact pair 14.

30 The disc is preferably provided with a series of holes 9 near its periphery and the pins may be fitted into selected holes as desired to determine the division of the fixed total time cycle into appropriate signal periods by stepping the camshaft CS by actuation of the solenoid S. The camshaft CS has an appropriate matching arrangement of cams to provide the several different signal combinations and the distribution of pins in the continuously rotating disc determines the periods of display of these several combinations, when the solenoid is connected to be actuated by the pin operated contacts.

45 The camshaft CS is carried in suitable bearings and has mounted on it a plurality of cams for controlling signal energizing contacts and control circuits. A solenoid S is arranged to advance the camshaft step-by-step through its cycle by means of a ratchet 20 on the camshaft and a pawl 15, energization and deenergization of the 50 solenoid moving the camshaft one step. Energizing the solenoid causes the pawl arm 16, pivoted at 17, to be pulled down against stop 81 against tension in spring 18, causing the pawl 15 to engage another tooth 19 on ratchet 20 which is prevented from moving backwards by dead pawl 23. Subsequent deenergization of solenoid S allows spring 18 to contract and return arm 16 against stop 82 thus advancing the camshaft counterclockwise one step or tooth in ratchet 20.

60 Two circuits are provided for energizing the solenoid S. One of these circuits includes the pair of contacts 13 which are adapted momentarily to be closed by each of the pins 11 in succession as each one of the pins 11 is rotated through the top of its circular path of movement. The other circuit includes contact pair 14 which is closed once in each cycle of the disc by the synchronizing pin 12 the purpose of which will subsequently appear.

65 The disclosed embodiment of the controller shows a 6 position camshaft and accordingly there are provided 5 pins 11 for energizing the solenoid to step the camshaft through all but one of its positions from which one position only the pin 12 and its cooperating contact pair 14 are

effective to advance the camshaft. Obviously if more camshaft positions are desired a greater number of pins 11 are inserted in disc 10 keeping the number of pins 11 always one less than the total number of camshaft positions, and corresponding teeth on ratchet 20.

In series with contacts 13 is a pair of contacts 21 which are closed by cam 31 in all positions of the cam-shaft except position 2, which is termed the A green rest position, in which pins 11 and contacts 13 are rendered ineffective to advance the camshaft by the opening of contacts 21. In all positions of the shaft except position 2 however, a circuit is completed to energize solenoid S upon the momentary closure of contacts 13 by one of the pins 11 from AC minus wire 101 over wires 48, 49, contacts 21, wire 44, contacts 13, wires 43, 42 and 40 and upon the immediate opening of contacts 13 to deenergize solenoid S and advance the camshaft one tooth or position.

A chart of camshaft positions is included in the lower left portion of the drawing and indicates by means of an X in a square that the contacts 21, 22, 24-29 are closed in a particular camshaft position.

Let it be assumed that the camshaft is standing in position 2, the A green rest position, in which contacts 24 and 29 operated by cams 34 and 39 are closed completing circuits from AC plus power, wire 180 over wires 74 and 79, respectively through A road green signal AG and B road red signal BR respectively to AC minus power. As described above contacts 13 and pins 11 are ineffective to advance the camshaft from this position 2 and the right of way remains accorded to the main road by energization of the AG signal.

A relay R is adapted upon actuation of one of the cross road traffic detectors D1 or D2 to be energized from AC minus via wire 58 detector D1 and wire 56 or wires 58, 57 detector D2, thence through wires 55, 53, relay R and wire 54 to AC plus. Such an actuation is "remembered" or locked-in by the holding circuit of relay R via wires 52, make contact r1, wire 51, contacts 22 closed by cam 32 in all positions of the cam-shaft except position 4, wire 50 to AC minus. When a detector actuation has energized and locked in relay R a circuit is prepared from AC minus over wires 48, 47, make contact r2, wire 46, over contacts 14, wires 45, 42, and 40 to solenoid S to energize solenoid S upon the next closure of contacts 14 by pin 12 and the camshaft is thereby advanced to its next position, position 3. The point on the cycle of dial 10 at which contacts 14 become closed may for simplicity be termed the synchronizing point and it will be noted that both a traffic actuation must have been locked in and the synchronizing point of the dial cycle must have been reached in order for the cam shaft to advance to position 3.

With reference to the cam chart it will be seen that in position 3 contacts 24 are broken and contacts 25 are made thus replacing the AG signal indication with the AY or "change" indication to A road traffic. When the dial 10 has been sufficiently rotated for the next pin 11 to close contacts 13 and reopen them thus energizing momentarily solenoid S the camshaft is advanced to position 4.

In position 4 cam contacts 25 and 29 are broken extinguishing the main road yellow change signal AY and the cross road red signal BR and right of way is accorded to the cross road. Cam contacts 26 and 27 are closed to il-

luminate the cross road green BG and the main road red AR. Contacts 22 are opened in this position thus deenergizing relay R.

5 A period of B road right of way ensues until the next pin 11 is rotated to close contacts 13 in turn momentarily energizing solenoid S to advance camshaft to position 5.

In position 5 there is no change of signal indications, the total cross road B right of way period 10 being the sum of the time periods of positions 4 and 5. In this position, however, contacts 22 are again closed by cam 32 so that actuations of the detectors D1, D2 which momentarily energize relay R are effective to maintain relay R energized to cause another cycle of operation of the camshaft and retransfer of right of way to the cross road when contacts 14 are next closed by synchronizing pin 12. Accordingly vehicles crossing the detectors in position 5, the last portion of 20 the cross road right of way period and which have insufficient time to pass the intersection are "remembered" and right of way is subsequently again accorded to the cross road to allow such vehicles to proceed. Position 5 is occupied ordinarily for only a few seconds and is terminated by the revolving of the next pin 11 to cause closure of contacts 13 advancing the cam-shaft in the manner described.

Contacts 21 are opened in position 6 extinguishing the cross road green signal BG and contacts 28 are closed to illuminate the cross road yellow change signal BY and upon the next closure of contacts 13 by one of pins 11 the cam-shaft is advanced into position 1.

30 In position 1 contacts 26 and 28 are broken by their associated cams 36 and 38 extinguishing cross road change signal BY and main road red signal AR and illuminating cross road red BR and main road green AG over contacts 24 and 29 35 which are closed by cams 34 and 39. The fifth and last one of pins 11 rotates into engagement with the contact pair 13 to cause operation of the solenoid S advancing the camshaft into position 2, the AG rest position once more.

40 In position 2 the signal indications remain the same as in position 4 but contacts 21 operated by cam 31 are open so that as pointed out above the solenoid operating circuit through contact pair 13 is ineffective to move the camshaft from this position.

45 If upon the next closure of contacts 14 by pin 12 no actuation has locked in relay R the cam-shaft CS remains in this position causing right of way to be displayed to the main road continuously for an entire cycle of dial 10 until contacts 14 are again closed by pin 12 or for a longer period, equal to an integral number of revolutions of the dial 10, until such time as contacts 14 are closed by synchronizing pin 12 and a vehicle actuation has locked in relay R.

50 The dial 10 has the same cycle length as the dial 10' at all other intersections of the group comprising the coordinated system and is kept continuously in step with dial 10' at any other intersection by the synchronous type motors M, M' which are supplied from the same power source. Accordingly the position of pin 12 on dial 10 in relation to the corresponding pin 12' in dial 10' in another controller determines the time relation between the interruption of right of way on the main road at the first intersection with interruption of right of way on the main road at the second. In a system of the so-called synchronized type in which interruption of right of way to the main road takes place simultaneously

at all intersections of the group the pin 12 and its corresponding pin 12' at all other intersections are so placed in their respective dials that each will close its respective contact pair 14 or 14' simultaneously, thus insuring that transfer of right of way accord from the main road at each intersection will occur at the same time.

Correspondingly a system of the so-called progressive type in which the time of transfer of right of way from the main road at the several intersections is staggered by a time period or offset to provide uninterrupted travel of platoons of traffic moving along the main road may be established by locating the pins 12, 12' at the several intersections at desired spacings around their respective dials so that each controller will provide the proper offset or time period before the point at which right of way transfer from the main road is permitted from a zero or reference point which may be marked correspondingly on each dial. Thus it will be seen that any desired time relationship between the time of transfer of right of way from the main road at the several intersections may be obtained by the relative positioning of the several pins 12, 12', and 11, 11'.

As an example of the "offset" adjustment of pins 12 and 12' the pin 12' is shown in a more advanced position in Controller II than the pin 12 in Controller I.

If it is desired at any intersection that right of way be transferred to the cross road whether or not there has been actuation of the cross road detector the switch 61 (or corresponding switch 61') is closed against contact 62 so that plus power is supplied directly via wires 63, 60 through contact pair 14 to the solenoid S to advance the camshaft upon operation of contacts 14 independently of operation of relay R.

Any desired allotment of the total time cycle of the dial 10 to the several signal periods may be made by suitably locating the pins 11 which are removably positioned in the face of the dial. Accordingly the length of the cross road right of way period may be different at different intersections without disturbing the settings for transfer of right of way from the main road at each intersection required by the progressive or synchronized program utilized.

Adjustment of the total time cycle of the dials 10, 10' may be made in any suitable manner as for example by introducing gears of different sizes in the drive of the dials so long as the total time cycle of each dial is the same as that of all the other dials.

It will be observed that the pin 12 in the controller, together with the cam 31 and contact 21 which interrupts the operation of the camshaft by pins 11 in camshaft position 2, resynchronizes the camshaft CS with dial 10 in every cycle of the camshaft. For example if one of the pins 11 should temporarily not effect proper movement of the camshaft thus causing the camshaft to be out of step with the dial and causing improper timing of the remaining signal periods in one cycle, the camshaft will be resynchronized with the dial when the camshaft is next advanced from position 2 by action of the long pin 12 to operate contact pair 14.

It will be understood that controllers I and II will ordinarily be identical, but for the purpose of illustrating an alternate form of the circuits for operating the solenoid by means of the pin actuated contacts, the arrangement of wiring of this part of controller II is shown in a different

form than that of controller I. The wiring of controller II for its solenoid S' includes the contacts 13' operated by pins 11', and the cam contacts 21' in one circuit for solenoid S' and includes contacts 14' operated by the long pin 12' and the traffic actuated relay contact r2' in another circuit for its solenoid and these several elements correspond with the similar elements in controller I, but the arrangement of these elements in the solenoid circuit is somewhat different, and the circuits for the solenoid in controller II will therefore be traced briefly below.

The circuit for operation of solenoid S' by action of pins 11' may be traced from AC minus power wire 101' via wire 85, solenoid S', wires 86, 87, 88, cam contacts 21', wire 89, pin operated contacts 13', wires 90 and 91 to AC plus power wire 100'. The circuit for operating solenoid S' by action of pin 12' may be traced from AC minus power wire 101' via wire 85, solenoid S', wires 86, 87, 92, contacts r2', wire 93, pin operated contacts 14', wires 94, 91 to AC plus power wire 100'.

In this alternate form of wiring used in controller II the switch 61', corresponding to switch 61 of controller I, cross connects wires 87, 93 when the switch is closed, to shunt contacts r2' when it is desired to have controller II act as a cyclically operated periodic controller instead of a traffic actuated type of controller.

Also for the purpose of illustration the cam-shaft CS' of controller II is shown in position 4, partway through its cycle, as a result of previous traffic actuation of one of the detectors in the cross road C. In the position shown the cam contact 22' is open so as to interrupt the lock in circuit of relay R' and release this relay from the effect of the previous traffic actuation, so that the camshaft CS' will stop when it reaches the rest position #2 unless a further traffic actuation occurs.

Summarizing, from the above description it will be seen that the present invention provides a controller of novel and simplified design for use in coordinated traffic control systems for a plurality of intersections. A number of controllers of this type when used to make up such a coordinated system provide great operating flexibility both in respect to the length of the several timed signal periods at each intersection and the relative times of certain signal changes at all the intersections when the controllers are used as vehicle actuated or non-vehicle actuated timers. Any desired relationship between the times of certain signal changes at the several intersections may be obtained even although no interconnecting wires are required other than the connection of all controllers to a common AC power source.

Each controller itself is of simple design of the rotating dial type having a number of pins in the dial which through a linking arrangement actuate a camshaft controlling the signal indications. As shown herein the linking arrangement may comprise a solenoid-operated ratchet and pawl mechanism having two solenoid energizing circuits. One such circuit embracing a pair of contacts closed at a predetermined point once in each cycle of the dial, in definite relationship at all intersections of a group, initiates a cycle of operation of the camshaft if a vehicle has actuated a vehicle detector in the approach to the intersection. The other solenoid energizing circuit includes contacts operated by other pins in the dial to maintain operation of the camshaft

through the rest of its cycle one such operation has been initiated. Accordingly the movement of the camshaft through a cycle of signal changes in response to traffic actuation is maintained in synchronism with operation of the rotating disc, and since the several rotating discs are maintained in synchronism the signal changes at the intersections are maintained in desired relationship.

It will be appreciated by those skilled in the art that the circuit closers might be mounted on a rotating disc to be operated by stationary pins set in fixed holes, in lieu of the stationary circuit closers operated by pins in the holes of a rotary disc as shown in the present embodiment.

It will also be appreciated by those skilled in the art that other forms of signal indications can be employed in lieu of the yellow signal indications in camshaft positions 3 and 6 for the respective streets, or that two camshaft positions could be employed in lieu of the one for the change indication for each street so that two stages of change indications could be provided for each street such as a dark signal period on one street followed by a red signal period for both streets for example at each change of right of way, with a corresponding change in the number of pins in dial 10 and in the number of teeth in the ratchet 20 and in the contour of the cams on camshaft CS.

It will also be understood that the number of holes 9 shown in the disc 10 is for simplicity of illustration only and that ordinarily a considerably larger number of closely spaced holes would be employed to give finer adjustment.

It will be further understood that other detectors may be connected in parallel with detectors D1, D2 and that push buttons or the like can be connected similarly for operation by pedestrians.

In this connection it will be understood that although the present disclosure represents a preferred embodiment of the invention this and other rearrangements of the parts or changes in the details of the parts may be made without departing from the spirit of the invention as defined by the claims.

I claim:

1. In a traffic signal system for the intersection of a main road and a cross road, a step-by-step right of way signaling controller adapted to be operated through a cycle including right of way signal conditions for the respective roads, a continuously operating synchronous motor, a circuit closer operated periodically by said motor, an electromagnetic stepping device for operating said controller one step at a time, means operating said stepping device at spaced time intervals through all of said signaling cycle except one condition in which right of way is indicated to the main road, means to be actuated by traffic in the cross road including a switch closed by such actuation, and means including an operating circuit having said circuit closer and said switch in series for operating said stepping device in said one condition responsive to closure of said switch and circuit closer.

2. In traffic control apparatus for the intersection of a main road and a cross road having traffic actuated means for the cross road and a step-by-step right of way signaling mechanism operable through a cycle of right of way signal indications for the respective roads responsive to actuation of the traffic actuated means, means operatively associating said mechanism with said

traffic actuated means including a shaft, a motor rotating said shaft, a circuit closer operated periodically by said shaft as the latter rotates, a second rotatable shaft, switches arranged to be operated by said second shaft in a predetermined sequence of switch combinations to provide for the right of way signaling cycle as said second shaft rotates, another switch opened by said second shaft in the main road right of way part of its cycle and closed in all other parts of its cycle, a second circuit closer operated periodically by the first mentioned shaft, said first shaft and circuit closer being arranged for operating said first circuit closer a plurality of times corresponding to one less than the number of the different switch combinations in the cycle of the second shaft during a cycle of rotation of the first shaft and for operation of the second circuit closer once in each cycle of rotation of said first shaft, a switch closed by actuation of said traffic actuated means, step-by-step means for operating said second shaft from one switch combination to another in its cycle when operated, an operating circuit for said step-by-step means including said first circuit closer and said another switch, and another operating circuit for said step-by-step means including said second circuit closer and the traffic actuated switch.

3. In a traffic control apparatus as in claim 2, electromagnetic holding means connected to said traffic actuated means to maintain said traffic actuated switch closed after closure by traffic actuation when operated, and an operating circuit for said electromagnetic means including an additional switch opened by said second shaft in the cross road right of way part of its cycle to release said traffic actuated switch and closed in all other parts of the cycle.

4. In a traffic control system for an intersection of a main road and a cross road having traffic actuated means for the cross road, a synchronous motor and a right of way signaling controller adapted to be operated through a cycle including right of way signal conditions for the respective roads in sequence at its intersection responsive to actuation of said traffic actuated means and in predetermined time relation with its associated motor under control of the latter; said controller comprising a step-by-step rotary signal switching mechanism providing the cycle of right of way signal conditions, an operating device for said mechanism to operate the latter from one step to another in its cycle responsive to momentary actuation, a circuit closer, a dial 50 rotated by said motor, pins placed in said dial so as to actuate said circuit closer momentarily one at a time as said dial is rotated, a second circuit closer placed out of range of said pins, an additional pin in said dial for actuating said second circuit closer momentarily at a predetermined point in the cycle of rotation of said dial, an operating circuit for actuating said operating device including the first circuit closer and a switch closed by said mechanism through all the 55 cycle of the latter except one condition in which right of way is indicated to the main road and another operating circuit for actuating said operating device including said second circuit closer and a switch closed by actuation of said traffic actuated means for the cross road, a holding means for maintaining the traffic actuated switch closed after traffic actuation and as long as said holding means is operated, and an operating circuit for said holding means including a switch closed by said mechanism in all its cycle except

one condition in which right of way is indicated to the cross road.

5. In a traffic control system for an intersection of a main road and a cross road having traffic actuated means for the cross road, a synchronous motor, and a right of way signaling controller adapted to be operated through a cycle including two successive right of way signal conditions for the respective roads in sequence at its intersection responsive to actuation of said traffic actuated means and in predetermined time relation with its associated motor under control of the latter; said controller comprising a step-by-step rotary signal switching mechanism providing the cycle of right of way signal conditions, an operating device for said mechanism to operate the latter from one step to another in its cycle responsive to momentary actuation, a circuit closer, a dial rotated by said motor, pins placed in said dial so as to actuate said circuit closer momentarily one at a time as said dial is rotated, a second circuit closer placed out of range of said pins, an additional pin in said dial for actuating said second circuit closer momentarily at a predetermined point in the cycle of rotation of said dial, an operating circuit for said operating device including the first circuit closer and a switch closed by said mechanism in all conditions of its cycle except the second successive right of way condition for the main road, and another operating circuit for actuation of said operating device including said second circuit closer and a switch closed by actuation of traffic actuated means for the cross road, a holding means for maintaining the traffic actuated switch closed after traffic actuation and as long as said holding means is operated, and an operating circuit for said holding means including a switch closed by said mechanism in all conditions of its cycle except the first right of way condition for the cross road.

6. In a traffic control system for a main road and a cross road having means actuated by traffic on the cross road and a right of way signaling mechanism adapted to be operated through a cycle including right of way signaling periods for each road, said mechanism including a plate member having a plurality of spaced holes circularly arranged, a circuit closer, a continuously operating timing motor providing relative rotary movement between said plate member and said circuit closer, a pin placed in a selected one of said holes, a step-by-step cyclic signaling switch having a plurality of steps in its cycle including right of way signaling steps for the respective roads, an electromagnetic device momentarily actuatable for operating said cyclic switch one step at a time, relay means connected to said traffic actuated means to be operated responsive to traffic actuation thereof to connect said electromagnetic device for momentary actuation by said circuit closer as the latter is actuated by said pin to operate said cyclic switch at one step of its cycle in which right of way is signaled to the main road and thereafter to be released in preparation for any subsequent traffic actuation, and means including other pins placed in selected others of said holes and connected with said cyclic switch to actuate said electromagnetic device to operate said cyclic switch through the remainder of its cycle after such operation in said one step.

7. In a traffic control system for a main road and a cross road having means actuated by traffic on the cross road and a right of way signaling

mechanism adapted to be operated through a cycle including right of way signaling periods for each road, said mechanism including a plate member, a circuit closer, a continuously operating timing motor providing relative rotary movement between said plate member and said circuit closer, pins spaced in selected positions in said plate member to actuate said circuit closer momentarily during such rotary movement, a 5 step-by-step cyclic signaling switch having a plurality of steps in its cycle including right of way signaling steps for the respective roads, an electromagnetic device momentarily actuatable for operating said cyclic switch one step at a time, 10 circuit means controlled by said cycle switch to connect said electromagnetic device for momentary actuation by first said circuit closer in all steps of said signal cycle except one in which right of way is signaled to the main road and to 15 disconnect said electromagnetic device in said one step, a second circuit closer placed out of range of actuation by said pins, an additional pin in said plate member placed and adapted to actuate said second circuit closer once in each cycle of rotary movement, relay means connected to said traffic actuated means to be operated responsive to traffic actuation thereof to connect said electromagnetic device for momentary actuation by said second circuit closer as the latter 20 is closed momentarily by action of said additional pin during such rotary movement to operate said cyclic switch at said one step of its cycle and thereafter to release in preparation for another actuation of the traffic actuated means.

25 8. In a traffic control system for the intersection of a main road and a cross road, a continuously rotating disc having a plurality of spaced holes in a circle concentric to its axis of rotation, pins placed in selected holes of said disc, a circuit closer placed to be operated by said pins, a 30 step-by-step cyclic signal controller having a cycle of signaling steps including separate steps for right of way to the respective roads and intervening steps for right of way change indications, an electromagnetic ratchet device for operating said controller one step at a time, a switch member closed by said cyclic signal controller in all except one of said controller steps in which one step right of way is indicated to the main road, an operating circuit for said electromagnetic device including said circuit closer and said switch member, another pin placed in said disc, a second circuit closer placed so as to be operated only by said another pin once in each cycle 35 of said disc, traffic actuated means in the cross road, a switch connected to be closed by said traffic actuated means responsive to traffic actuation thereof, and an auxiliary operating circuit for said electromagnetic device including said last named switch and said second circuit closer.

40 9. A traffic control system for a main road and cross road including electric right of way signals for the respective roads, means actuatable by traffic in the cross road, a step-by-step cyclic switch actuatable for operating said signals through a cycle including right of way periods for the respective roads, an electromagnetic device for so actuating said cyclic switch, a continuously operating motor, a disc rotated by said 45 motor, pins adjustably spaced in said disc, a circuit closer in position to be operated momentarily by each of said pins as said disc is rotated, a second circuit closer, in position not to be actuated by said pins, an auxiliary pin in said disc in position to operate said second circuit

50 55 60 65 70 75

closer at one point in each cycle of rotation of said disc, a relay, a third circuit closer opened by said cyclic switch only in one step of the latter near the end of the main road right of way period, a fourth circuit closer operated by operation of said relay, a normal operating circuit for said electromagnetic device including the first and third circuit closers in series, an auxiliary operating circuit for said electromagnetic device including said second circuit closer and said fourth circuit closer in series, an operating circuit for said relay connected with said traffic actuatable means to operate said relay responsive to traffic actuation, another circuit closer opened by said cyclic switch only in one step of its cycle during the cross road right of way period, and a lock-in circuit for said relay including said other circuit closer.

10. In a traffic right of way signaling apparatus for road intersections having one rotary member providing a cycle of right of way signaling positions to determine several combinations of signaling indications to be displayed in the several positions of the cycle and a second rotary member having a number of actuating elements adjustable in relative position on said member to determine a total length and subdivision of a time cycle into at least as many parts as the number of said signaling positions, means including a traffic actuated device associated with one of the intersecting roads to connect said second rotary member to said first rotary member responsive to traffic actuation of said device for operation of said first rotary member through its cycle by said actuating elements to provide a right of way signaling period for traffic actuating said device.

11. In a street traffic right of way signaling apparatus the combination of a rotary signal controller having a cycle of operating positions to provide for a plurality of separate right of way signaling conditions in such cycle, a step-by-step driving device adapted to be operated momentarily to rotate said controller from one position to another in said cycle, a shaft, a motor connected to rotate said shaft, a circuit closer arranged to be operated by said shaft at spaced intervals a plurality of times in one cycle of rotation of said shaft, switches forming a part of said controller and operated cyclically as said controller rotates, an operating circuit for said driving device including said circuit closer and

one of said switches open in one right of way position of the cycle of said controller and closed through the remainder of such cycle, a second circuit closer arranged to be operated 5 momentarily by said shaft at a predetermined point in its cycle of rotation, traffic actuated means including a switch closed responsive to actuation by traffic, an operating circuit for said driving device including said second circuit closer 10 and said traffic actuated switch for operating said driving device at said one position of said controller cycle, a holding means for maintaining said traffic actuated switch closed after actuation thereof by traffic and as long as said holding means is operated and an operating circuit for said holding means including one of said switches opened only in another position of the cycle of 15 said controller corresponding to a right of way signaling condition for traffic actuating said 20 traffic actuated switch.

12. A traffic control system for a main road and cross road including electric right of way signals for the respective roads, means actuatable by traffic in the cross road, a step-by-step 25 cyclic switch actuatable for operating said signals through cycle including right of way periods for the respective roads, an electromagnetic device for so actuating said cyclic switch, a continuously operating motor, a shaft rotated by 30 said motor, a circuit closer operated momentarily a plurality of times in each cycle of rotation of said shaft, a second circuit closer operated by said shaft once in each cycle of rotation of said shaft, a relay, a third circuit closer opened by 35 said cyclic switch only in one step of the latter near the end of the main road right of way period, a fourth circuit closer operated by operation of said relay, a normal operating circuit for said electromagnetic device including the first and third circuit closers in series, an auxiliary operating circuit for said electromagnetic device including said second circuit closer and 40 said fourth circuit closer in series, an operating circuit for said relay connected with said traffic actuatable means to operate said relay responsive to traffic actuation, another circuit closer opened by said cyclic switch only in one step of its cycle during the cross road right of way period, and a locking circuit for said relay including 45 said other circuit closer.

HARRY A. WILCOX.
